CLAIM

The ornamental design for a dental package, as shown and described.

DESCRIPTION

FIG. 1 is a perspective view of a dental package, embodying my new design;

FIG. 2 is a top view thereof;

FIG. 3 is a bottom view thereof;

FIG. 4 is a front elevational view thereof;

FIG. 5 is a right side elevational view thereof; the left side elevational view thereof being a mirror image; and,

FIG. 6 is a rear elevational view thereof.
